SPRAYER WITH PUMP AND SCREEN
 Vincent Santarelli, 6509 Heintz Ave., Detroit, Mich.
 Filed Feb. 18, 1960, Ser. No. 9,513
 3 Claims. (Cl. 222—189)

My invention relates to a new and useful improvement in a sprayer in which liquid is forced from a tank under pressure through the action of a pump. The invention relates to that type of sprayer in which the pump is reciprocated at one end in a well and particularly relates to the method of mounting the well into position.

It is an object of the present invention to provide a well of this type so constructed and arranged that it may easily and quickly be removed from position in the tank and replaced therein.

Another object of the invention is the provision of the mounting of the well having a strainer attached thereto so that the strainer may be easily and quickly removed for cleaning purposes.

Another object of the invention is the provision of a pump mechanism so arranged and constructed that it will be highly efficient in use, economical of manufacture, durable and compact.

Other objects will appear hereinafter.

It is recognized that various modifications and changes may be made in the detail of the structure illustrated without departing from the invention, and it is intended that the present disclosure shall be considered to be but the preferred embodiment.

Forming a part of this application are drawings in which:

FIG. 1 is a side elevational view of the sprayer embodying the invention.

FIG. 2 is a top plan view of the invention.

FIG. 3 is a longitudinal sectional view taken on line 3—3 of FIG. 2, with parts broken away.

FIG. 4 is a slightly enlarged sectional view of the well shown in FIG. 3.

FIG. 5 is a fragmentary sectional view taken on line 5—5 of FIG. 3.

FIG. 6 is a fragmentary sectional view taken on line 6—6 of FIG. 5.

As shown in the drawings, I use a tank 9 in which the liquid to be discharged therefrom is deposited. This tank 9 has a cover 10 having an opening 11 formed therein closed by the closure 12. Formed in the top 10 is an opening 13 lined by a suitable sealing gasket 14 in which is reciprocally mounted the tube 15. The upper end of this tube 15 is closed by the cap 16 having a neck 17 projecting upwardly therefrom and projecting therefrom is a fitting 18 on which one end of a flexible tube 19 is mounted. A tube 69 is connected at one end in the neck 19 to communicate with the interior of the fitting 18 and serves as a means of conducting liquid to the flexible tube 19. Pivotedly mounted at one end of the bracket 20 which is mounted on the container 9, is an operating handle 21. An angularly turned end 22 of a rod 23 is projected through the handle 21 and extended upwardly and provided with an angularly turned end 24 which projects through an opening formed in the neck 17. A back-rest 25 is mounted on one side of the container 9.

The lower end of the tube 15 is reduced at 28 and is closed by a disc 30 mounted therein and projecting inwardly of which is an internally threaded neck 31. Threaded into this neck 31 is an externally threaded tube 32 which has tongues 33 punched inwardly to retain the ball 34 in position. This ball 34 is designed to serve as a closure for the opening 35 formed in the closure plate 35a which is fixedly mounted on the part 32. Openings 35b are formed in this plate 35a. The plate 35a serves

2

as a retainer for retaining the flexible plunger cap 29 fixedly mounted on the lower end of the portion 28. Openings 47 are also formed in the upper end of the tubular body 32.

5 A well 36 is provided and the lower end is constructed in an internal diameter as at 37. This lower end is closed by a disc 38 having a slot 39 formed centrally therethrough and pressed upwardly at the central portion thereof. Projected through this slot is a tubular member 41 at the upper end of which is secured a valve plate 40. Secured to the lower end of the member 41 is a limiting plate 42, which is of less diameter than the length of the slot 39.

10 The tank 9 is provided with a bottom 56 which is pressed outwardly to provide a trough 27 which underlies the operative location of the well 36. The lower end of the well 37 is provided with a peripheral flange 43 and secured to this flange and projecting outwardly from one side of the well 37, is a screen 44 which has its opposite edges 45 turned to extend in a single plane.

15 Mounted on the bottom 56 of the tank 9 is a horseshoe plate 46 which has the inner edges thereof elevated above the bottom 56 so that the well with the screen 44 attached thereto may be slid inwardly of the open end of this horseshoe retainer. In sliding inwardly, the flange 43 and the edges 45 of the strainer engage below the retainer 46 and thus the mechanism is held in fixed position. When fully thrust inwardly of the member 46, the well 36 will be held in operative position in alignment with 20 the pump plunger 15.

25 In operation, upon rocking the handle 21, the rod 23 will effect a reciprocal movement of the plunger 15 so that the lower end moves upwardly and downwardly of the well 36. In the upward movement, the ball 34 will move to closing position and the valve plate 40 will move upwardly to open position so that liquid will be drawn into the well 36 from the interior of the tank 9. On the downstroke, the ball 34 will be forced upwardly into open position and the valve plate 40 will move into closed position so that the liquid entrapped in the lower end of the well will be forced upwardly around the ball 34 and outwardly through the openings 47 and the slots 48 into the interior of the reduced portion 28 of the plunger 15. As this movement continues, the liquid entering the 30 plunger 15 will travel upwardly through the pipe 69 and thence outwardly from the flexible tube 19.

35 When it is desired to remove the well from the container, it is necessary that the rod 23 be disconnected from the neck 17 whereupon the pump plunger 15 may be raised upwardly to clear the upper end of the well 36. The well 36 may then be removed by pulling the same outwardly toward the open end of the horseshoe retainer and thus the well and the strainer will be accessible for 40 cleaning purposes.

45 55 What I claim is:

1. In a sprayer of the class described having a liquid containing tank and a reciprocating pump plunger and means for reciprocating said plunger; a tubular well open at its upper end for reception of the lower end of said plunger; a closure for the lower end of said well; an opening formed in said closure; a valve in said well for closing said opening, said valve moving to open position upon drawing liquid into said well and to closing position upon forcing said liquid out of said well; a screen mounted on the lower end of said well and extending outwardly therefrom and lying with its edges in engagement with the bottom of said tank and elevated above the same between the opposite edges thereof and having a plurality of perforations formed therein; a peripheral flange projecting outwardly from the lower end of said well; a bottom on said tank; and a U-shaped retaining

member mounted on said bottom of said tank and placed with its inner edges upwardly from the bottom of said container for engagement with the opposite edges of said strainer and said flange of sliding of the same inwardly upon said retainer.

2. In a sprayer of the class described having a liquid containing tank and a reciprocating pump plunger and means for reciprocating said plunger; a tubular well open at its upper end for reception of the lower end of said plunger; a closure for the lower end of said well; an opening formed in said closure; a valve in said well for closing said opening, said valve moving to open position upon drawing liquid into said well and to closing position upon forcing said liquid out of said well; a screen mounted on the lower end of said well and extending outwardly therefrom and lying with its edges in engagement with the bottom of said tank and elevated above the same between the opposite edges thereof and having a plurality of perforations formed therein; a peripheral flange projecting outwardly from the lower end of said well; a bottom on said container; a retainer mounted on said bottom in alignment with said flange and having oppositely disposed edges connected at one end by a connecting member, the inner portions thereof being elevated relatively to said bottom; and, a peripheral flange on the lower end of said well; a strainer mounted and projecting outwardly from said well and having the central portion thereof elevated relatively to said bottom and its opposite end edges angularly turned to lie in the same plane as said flange, said flange and said edges being slidably into engagement with and lying beneath the inner edges of said retainer.

30

3. In combination: a sprayer liquid receiving tank; a reciprocating plunger inserted into one end of said tank; means for reciprocating said plunger; a bottom on said tank; a tubular well open at its open end for the reception of the lower end of said plunger; a check valve on the lower end of said plunger for permitting liquid to enter said plunger and prevent the flow of same from said plunger; an outlet opening in the open end of said plunger; a conducting tube in said plunger extending adjacent the lower end thereof and connected at its upper end to the outlet of said plunger; a closure for the lower end of said well; an opening formed in said closure; a valve in said closure for closing said opening, said valve moving to open position upon drawing liquid into said well and to closing position upon attempted forcing of liquid out of said well; a peripheral flange projecting outwardly from the lower end of said well; a screen mounted on the lower end of said well and extending outwardly therefrom and lying with its edges in engagement with the bottom of said container and elevated above said bottom between the opposite edges thereof and having a plurality of perforations formed therein; and, a retainer mounted on the bottom of said tank for engaging said peripheral flange and opposite edges of said screen for detachably mounting the same in position on the bottom of said tank.
